ABSTRACT: A separator for sliced onions operable to separate the rings thereof for use in the production of "French fried onion rings". Sliced onions are delivered to a platform having a series of perforations throughout its extent, and through which plungers periodically project, the plungers being successively projected in such manner as to agitate and vibrate onion slices delivered to an intake end of the platform. The plungers projecting through the perforations of the platform engage the onion slices and separate them into rings. Means is provided to advance the slices and rings toward a discharge end of the platform with the slices all separated into rings, except for small ones around the hearts of the onions, by the time they reach the discharged end. The platform is flexible and the plungers have shoulders which knock against the platform to vibrate it, thus jostling the onions and rings to more efficiently separate the onions into rings. By omitting plungers from some of the perforations, the onion hearts may be discarded before the rings reach the discharge end of the platform, those small enough passing through the perforations from which the plungers are omitted. The means to advance the onions along the platform may be gravity for a platform inclined slightly downward, or circulated water in which case the platform may be inclined slightly upward.

ONION RING SEPARATOR

BACKGROUND OF THE INVENTION

Heretofore onions have been peeled and sliced manually and the onion slices separated into rings manually. The existing method of preparing onion rings for batter and breading before they are French fried is primarily done by hand operation. Some machines are available for cutting the ends from the onions such as shown in Boyer Pat. No. 2,961,023, but usually this is done by hand and the onions are hand peeled, and some machines such as bread slicing machines are available for slicing the onions preparatory to separating the rings thereof.

I have not been able to find any satisfactory peeling machines for onions. My copending application Ser. No. 827,683, filed May 26, 1969 discloses an end cutting machine for cutting the root and stem from the onion in a manner suitable for delivery to a peeling machine such as shown in my copending application Ser. No. 827,672, filed May 26, 1969, from which the peeled onions may be delivered to a slicing machine such as shown in my copending application Ser. No. 745,900, filed July 18, 1968. The slicing machine may then deliver the onion slices to the presently disclosed onion ring separator.

Heretofore machines of shaker type and tumbling barrels have been used for onion ring separation purposes but are inefficient. Another method is submerging in boiling water, but mostly the rings have heretofore been separated by hand.

My present invention contemplates a mechanical onion ring separator which will separate sliced onions into rings in an automatic manner and can be arranged as a fourth machine in an onion ring production line wherein my end cutting machine, my peeling machine and my slicing machine as just referred to precede the present onion ring separator.

One object of the invention is to provide a comparatively simple and inexpensive separator in which a platform is provided to receive sliced onions at one end and deliver onion rings at the other end.

Another object is to provide separating means associated with the platform in the form of plungers distributed across the span of the platform and projectable, each through an opening thereof, to a short distance above the upper surface of the platform so as to engage sliced onions and knock and vibrate them to separate them into their individual rings.

Another object is to provide means for projecting the plungers comprising a cam shaft having a succession of cams thereon operable to periodically depress the plungers and then let them knock against the bottom of the platform.

Still another object is to provide means for actuating shoulered plungers comprising cams which have drop lobes, the plungers being spring biased toward the bottom of the platform and their shoulders thereby operable to impart knocking action thereagainst due to the spring bias.

A further object is to provide the succession of cams on a single cam shaft and arrange for the lobes thereof to be so spaced circumferentially of the cam shaft so as to provide an undulating sequence of plunger projections through the openings of the platform for most effective separation of the onion slices into their individual rings.

Still a further object is to provide a platform which is somewhat flexible to accentuate the undulating action and accordingly the onion ring separation capability of the machine.

An additional object is to provide the platform and plungers submerged in a tank of water to reduce the bacteria count and circulate the water in order to use the flow thereof as a means to advance the onion slices and rings along the platform from the intake end thereof to the discharge end thereof.

Another additional object is to provide a sump, pump, valve and nozzle arrangement for circulating the water in such manner as to control the circulation by adjustment of the valve and utilize the discharge from the nozzles to circulate the water in the proper direction for advancing the onion rings along the platform as desired.

Still another additional object is to provide a modified form of the invention in which the separating operation is performed dry, the platform being inclined downwardly and arranged to permit automatic separation of hearts from the onion slices through perforations of the platform which do not have plungers in them.

BRIEF SUMMARY OF THE INVENTION

10 A separator for onion rings is provided having a frame on which a perforated flexible platform is mounted, means being provided to vibrate the platform for separating onion slices delivered to the platform into rings and discharge the rings from the platform. By submerging the platform and plungers in water and circulating the water a means is provided for conveying the onion slices and rings along the platform from the intake end thereof to the discharge end thereof. Provision is also made for separating hearts from the onion rings if desirable.

BRIEF DESCRIPTION OF THE DRAWINGS

FIG. 1 is a side elevation, partly in section, showing my onion ring separator;

25 FIG. 2 is a vertical sectional view thereof on the line 2-2 of FIG. 1;

FIG. 3 is a plan view of FIG. 1;

FIG. 4 is a vertical sectional view taken on the lines 4-4 of FIGS. 1 and 3;

30 FIG. 5 is an enlarged vertical sectional view on the line 5-5 of FIG. 3 showing the vibrating action imparted to the platform of my onion ring separator by plungers of the apparatus;

FIG. 6 is a similar sectional view showing a modified form of the invention; and

35 FIG. 7 is a view similar to a portion of FIG. 1 involving the modification of FIG. 6.

On the accompanying drawings I have used the reference character F to indicate in general a supporting frame for my onion ring separator. The frame F may be formed of square 40 stainless steel tubing wherein the elements thereof are welded together. An open top tank T is supported in the frame F, and the frame includes a peripheral arrangement of angle shaped elements 10 as shown in cross section, particularly in FIGS. 1 and 4, for supporting a platform P. The periphery of the platform is loosely supported by the angle elements 10 by means of a peripheral downwardly extending flange 12. The platform is preferably formed of flexible plastic material such as polyurethane or the like and is provided with a plurality of perforations 14 which, as shown in FIGS. 4 and 5 for instance, are reinforced by bosses 16, the entire platform, it flanges 12 and its bosses 16 being molded in one piece.

Projectable through each perforation 14 is a plunger 18 having a shoulder 20. The plungers are arranged in rows with those in each row supported on a shaft 19 shown in FIG. 4, and the shaft is supported by a plunger actuating yoke 22, the central portion of which is pivoted to one end of a Z shaped plunger actuating arm 24. The plurality of arms 24 rest on a pivot shaft 26 supported by the frame F, and are in turn actuated by a cam shaft 28 having thereon a cam 30 for the other (upper) end of each arm 24. The arms 24 have projections 32 engaging the cams 30, which may be provided with rollers if desired. The cams have preferably drop-type lobes as illustrated in FIG. 4 which are oriented alternately 180° apart. A 55 spring 34 for each arm 24 is adapted to bias each projection 32 toward its cam 30. The spring is mounted on a rod 36 connected with the upper end of the arm 24 as shown in FIG. 4 and provided with adjusting nuts 38 for the tension of the spring 34. All rods 36 extend slidably through a bar 40 supported by the frame F.

For rotating the cam shaft 28 a motor 42 including suitable stepdown gearing drives a shaft 44 which is operatively connected to the cam shaft 28 as by a chain 46 shown in FIG. 3.

The tank T is adapted to contain water in which the platform P and the plungers 18 are submerged, the approximate

water level being shown at 48. At the right-hand end of the tank T in FIG. 1 is a sump 50 to receive water flowing off the platform P, and a pipe 52 leads therefrom to a pump 54. A pipe 56 leads from the outlet of the pump 54 to a regulating valve 58 and from the valve a pipe 59 leads to a manifold 60 across the left end of the tank in FIG. 1. FIG. 3 also shows the sump 50 at the right-hand end and the manifold 60 at the left-hand end. A plurality of nozzles 62 direct water from the manifold 60 toward the platform P as indicated by the arrow 63 in FIG. 1. At the top of the sump 50 is a roller 64 suitably driven as by gears 66 and a chain 68 from the motor shaft 44.

In FIG. 6 a modification is shown wherein the plungers 18 are omitted from some of the openings 14, such openings being designated 14a in this FIG. and shown of larger diameter. An onion heart 74 is shown dotted in one of the openings 14a to illustrate separation of hearts from the larger rings used for French-frying purposes.

FIG. 7 shows the platform of FIG. 6 used as a "dry" type of separator by omitting the tank T and pump system described in FIGS. 1 to 4 inclusive. Preferably the platform P is inclined slightly downward for a purpose which will hereinafter appear.

FIGS. 1 and 7 show in dot-and-dash lines a delivery conveyor 70 and a take-away chute 72 for delivering sliced onions, as from the slicing machine of my copending application Ser. No. 745,900 hereinbefore referred to, to the onion ring separator (intake end thereof) and for receiving the onion rings from the discharge end of the platform P and delivering them to mechanism and/or personnel for further processing toward the finished French fried onion rings.

PRACTICAL OPERATION

In the operation of my onion ring separator, sliced onions are delivered by the delivery conveyor 70 at the left-hand end of FIGS. 1 and 3 while the pump 54 is in operation to cause a circulation of water according to the arrow 63 which circulation tends to advance the slices of onions and the rings separated therefrom along the platform P to the roller 64 over which the separated rings are rolled to prevent them from entering the sump 50. To somewhat retard the movement of the onion slices and rings along the platform it is inclined slightly upward as shown in FIG. 1 which inclination, in combination with a regulated flow of water by means of the valve 58 produces the desired speed of travel of the onion slices and rings through the separator. Also this arrangement gives a greater depth of water at the intake end of the platform than at the discharge end which aids in the separating action on the onion slices.

As the cams 30 rotate they cause the plungers 18 to rise and fall as shown in FIG. 5, accomplished of course by the rotation of the cams which have alternate lobes 180° apart. Accordingly while one row of plungers is rising the next row is falling and vice versa. By the use of drop-type lobes and spring bias produced by the springs 34, the plungers are gradually lowered and suddenly elevated so that their shoulders 20 knock against the lower ends of the hubs 16 as shown by the second and fourth plungers in FIG. 5. Since the platform is flexible it will bend as illustrated from the normal level formation shown by dot-and-dash lines when the shoulders 20 engage and elevate the hubs 16, thus giving an undulating motion to the platform P which I find very effective in separating the onion slices into their individual rings. Also the projection of the plungers above the top of the platform aids in this respect and the undulating motion accentuates the separating action of the platform on the onion slices.

The turbulence of the water in the tank T caused by the operation of the pump 54 also helps to separate the onion slices into individual rings and keeps the bacteria count down, an important consideration from the standpoint of sanitation as required by pure food laws.

Small installations with limited production capacity are possible without the provision of a tank T and water therein as shown in the modified embodiment of my onion ring separator

of FIG. 7. With this "dry" type of separator it is also possible to omit the plungers from some of the openings 14 (such as 14a in FIG. 6) and these will serve as a means to receive onion hearts and permit them to fall through and thus be separated from the onion rings suitable for French-frying purposes. The size of these openings may be varied for gauging the sizes of onion hearts to be discarded, being shown larger in FIG. 6 than the ones for the plungers 18.

By inclining the platform P in FIG. 7 slightly downward gravity cooperates in causing the onion slices and rings to advance from the intake end of the platform toward the discharge end thereof.

I claim:

- 15 1. An onion ring separator comprising a perforated platform having an intake end and a discharge end, means for delivering onion slices to said intake end, means for separating the onion slices into their separate rings comprising plungers projectable through said perforations, and means to periodically cause projection thereof to engage the onion slices and rings and impart a bouncing movement thereto with respect to said platform.
- 20 2. An onion ring separator in accordance with claim 1 wherein means is provided to advance said onion slices and rings from said intake end of said perforated platform to said discharge end thereof.
- 25 3. An onion ring separator in accordance with claim 1 wherein said last means comprises a cam shaft, and cams thereon which cooperate with said plungers to periodically elevate them.
- 30 4. An onion ring separator in accordance with claim 3 wherein said plungers have shoulder means engagable with the bottom of said platform to knock thereagainst and thereby impart vibrations thereto.
- 35 5. An onion ring separator in accordance with claim 4 wherein said platform is composed of flexible material to permit bending thereof when engaged by said shoulder means to thereby accentuate the vibrations thereof.
- 40 6. An onion ring separator in accordance with claim 3 wherein said cams have drop-type lobes and said plungers are spring biased in a direction toward said platform.
- 45 7. An onion ring separator in accordance with claim 4 wherein each of said cams has a drop-type lobe and said plungers are spring biased in a direction toward said platform.
- 50 8. An onion ring separator in accordance with claim 5 wherein said plungers are spring biased toward said cams and said shoulders are thereby biased toward said platform.
- 55 9. An onion ring separator in accordance with claim 2 wherein said platform is composed of flexible material to permit bending thereof, said means to periodically cause projection of said plungers through the perforations of said platform comprises a cam shaft, cams thereon operatively associated with said plungers, and said plungers have shoulder means to engage the bottom of said platform and thereby impart vibrations thereto to jostle the onion slices and rings thereon.
- 60 10. An onion ring separator in accordance with claim 9 wherein the perforations of said platform are arranged in lateral and longitudinal rows, means for connecting the plungers of each row together, and each of said connecting means being responsive to a separate cam on said cam shaft.
- 65 11. An onion ring separator in accordance with claim 10 wherein each of said connecting means is spring biased toward said platform and said plungers have shoulder means to knock against the bottom of said platform due to such spring bias.
- 70 12. An onion ring separator in accordance with claim 11 wherein said cams are of the drop-lobe type to accentuate the knocking action of said shoulder means against said platform.
- 75 13. An onion ring separator in accordance with claim 9 wherein alternate cams on said cam shaft have their lobes oriented 180° apart.
14. An onion ring separator in accordance with claim 5 wherein a frame is provided for said onion ring separator, said platform has its side edges loosely mounted thereon, and said cam shaft is journaled on said frame.

15. An onion ring separator in accordance with claim 14 wherein the intake and discharge ends of said platform are also loosely mounted on said frame.

16. An onion ring separator in accordance with claim 1 wherein a tank is provided, and said perforated platform and said plungers are located therein and submerged under water therein.

17. An onion ring separator in accordance with claim 16 wherein means is provided for circulating the water in said tank by directing it over said perforated platform from the intake end toward the discharge end thereof.

18. An onion ring separator in accordance with claim 17 wherein said platform is inclined upwardly from said intake end to said discharge end thereof.

19. An onion ring separator in accordance with claim 17 wherein said means for circulating comprises a pump, and valve means for regulating the degree of circulation and thereby the rate of advancement of said onion slices and rings from said intake end to said discharge end of said platform.

20. An onion ring separator in accordance with claim 17 wherein said water circulating means includes a sump at the discharge end of said perforated platform and nozzle at the intake end thereof directed toward said discharge end.

21. An onion ring separator in accordance with claim 19 wherein said platform is slightly inclined upwardly from said intake end thereof to said discharge end thereof, and means is provided for advancing said onion slices and rings along said platform to the discharge end thereof.

22. An onion ring separator in accordance with claim 1

wherein plungers project through only some of said perforations and the remaining perforations provide for exit of onion hearts therethrough before reaching said discharge end of said platform.

23. An onion ring separator in accordance with claim 1 wherein the perforations of said platform are arranged in rows, said plungers are provided for only some of said rows and the remaining rows are provided for the passage therethrough of onion hearts gauged by the diameters of the perforations of said remaining row.

24. An onion ring separator in accordance with claim 1 wherein said perforated platform is slightly inclined downwardly from said intake end thereof to said discharge end thereof whereby the onion rings and slices gravitate from said intake end to said discharge end.

25. An onion ring separator in accordance with claim 16 wherein a roller is provided at said discharge end of said platform, and means is provided for rotating said roller to discharge onion rings from said platform and away from the discharge end thereof.

26. An onion ring separator in accordance with claim 25 wherein means is provided for withdrawing water from the discharge end of said platform and recirculating it, discharging the same at said intake end and toward said discharge end, the intake for said pump means being in the form of a sump beyond the discharge end of said platform, and said roller being located at the top thereof to cause onion rings to pass over said sump.
